JAMES D. KINCAID, OF BOWLING GREEN, MISSOURI.

Letters Patent No. 67,772, dated August 13, 1867.

IMPROVEMENT IN PLOUGHS.

The Schedule referred to in these Letters Patent and making part of the same.

TO ALL WHOM IT MAY CONCERN:

Be it known that I, JAMES D. KINCAID, of Bowling Green, in the county of Perry, and State of Missouri, have invented a new and useful Improvement in Gang and Breaking-Ploughs; and I do hereby declare that the following is a full and clear description thereof, reference being had to the accompanying drawings, and to the letters of reference marked thereon.

This invention relates, firstly, to a device for holding the plough or ploughs steadily in position, laterally and also down into the ground, during the operation of ploughing, the device being especially needed in and adapted to a breaking-plough, in the use of which the rough and uneven nature of new ground often causes great trouble in its guidance. The invention relates, secondly, to the device for lifting the plough or ploughs up out of the ground; and, thirdly, to the mode of attaching the ploughs to the frame.

To enable those skilled in the art to make and use my improved plough, I will proceed to describe its construction and operation.

Figure 1, of the drawings, is a longitudinal section of the improved plough.

Figure 2 is a rear end elevation of it.

Figure 3 is a plan.

The frame A, which sustains the ploughs, is mounted on the wheels B B in much the usual manner of common gang-ploughs, the principal difference being the construction of the wheels, which, in this instance, are made of the same height and somewhat larger in diameter than those usually employed.

The device for guiding and directing the plough or ploughs laterally is as follows, viz: There are two rock-shafts or rollers, C C, which have their bearings in the top of the frame A. On the forward ends of these shafts or rollers are cranks or elbows c, and on the rear ends of them are similar cranks or elbows c¹ diametrically opposite those at the forward end. The outer ends of the elbows c are connected, by means of the chains c² with the lever C', which is in such convenient proximity to the seat S as to be operated by the driver while seated thereon. The outer ends of the elbows c¹ are connected, by means of the chains c³, with the upper part of the plough-post D. Other chains c⁴ are attached to the said post D lower down, and also to the frame A, as an additional lateral stay for the ploughs, the latter chains being tight only when the ploughs are down in the ground.

When the parts are thus arranged, and the ploughs are down in the ground, the driver, by depressing the lever C', will raise the elbows c and depress c¹, and the chains c³ will, by the operation, be made to draw tightly on the post D, as shown in fig. 2, and at the same time the said chains will also draw down on the post D, as is also shown in fig. 2. The effect of this will be to steady and guide the plough laterally, and also to hold it down in the ground while at work.

The device for lifting the ploughs up consists of the levers E, pivoted on the fulcrum-arms e e, the chains or rods E', which connect the plough-beams with the back ends of the levers, and the spring-catch e', attached to the frame A immediately below the driver's seat, and a little in front thereof, so as to allow of its operation by his feet. The fulcrum-arms e e are simple L-shaped rods attached to the frame A. The upper or horizontal parts of these fulcrum-arms might form a continuous rod across the machine from side to side.

The attachment of the forward ends of the plough-beams to the frame A is made by means of the clevis d, the undulating bar d', and the stays d''. The undulating bar is a U-shaped rod, having its ends pivoted in the stays d'', which are attached to the bottom side of the frame A. The clevis d is attached to the forward end of the plough-beam in the usual manner. By this arrangement of the parts the plough is enabled to run steadily in the ground, without reference to the vertical undulations of the wheels, caused by the asperities of the surface of the field, the undulations of the bar d' taking up that given it by the frame A without imparting it to the plough-beam.

Having described my invention, what I claim, is—

1. The rock-shafts or rollers C C and their cranks or elbows c c¹, the lever C', and the chains c³, when combined with the post D of the plough, as and for the purposes herein set forth and described.
2. I claim the combination and arrangement of the levers E, the chains or rods E', the fulcrum-arms e e, and the spring-catch, substantially as described and set forth.
3. I claim the attachment of the plough-beams to the frame A by means of the device d d' d'', substantially as described and set forth.
